IGNITION AND SAFETY CONTROL SYSTEM
FOR FUEL BURNERS

Charles K. Strobel, Pittsburgh, Pa., and Samuel G. Eskin, Los Angeles, Calif., assignors to Robertshaw Thermostat Company, Youngwood, Pa., a corporation of Pennsylvania

Application August 8, 1945, Serial No. 609,626

6 Claims. (Cl. 158—117.1)

1

This invention relates to ignition and safety control systems for fuel burners and, more particularly, to electrically operated systems therefor.

Systems of the type indicated may be arranged so that an electromagnetic safety valve may be opened when a main switch is closed and the fuel supply turned on. The fuel is then ignited by an electric igniter controlled by the main switch and after the expiration of a starting period the igniter is disconnected by operation of a timing device. The valve then either remains open or is closed by varying the current supply thereto according to variations in the resistance of a thermal resistor exposed to the heat of the burning fuel.

Where an electromagnetic relay is employed in conjunction with the timing device it is apparent that power consumption and operating noise would be reduced if the power consuming element of the relay were disconnected after the starting period. It is, therefore, an object of this invention to render the system substantially noiseless during the running period.

Another object of the invention is to effect a saving in power consumption in the operation of safety and ignition systems.

Another object of the invention is to insure reliable operation of the system in performing its functions during the starting and running periods when normally operated.

Another object of the invention is to render the system sufficiently flexible as to length of the starting period to provide a wide range of operation.

Another object of the invention is to place the timing device in condition for another starting period immediately upon inception of the prior running period.

Other objects and advantages will become apparent from the following description taken in connection with the accompanying drawing, wherein:

Fig. 1 is a schematic view of part of a safety control apparatus for a gaseous fuel burner embodying this invention;

Fig. 2 is a circuit diagram showing the electrical connections; and

Figs. 3 and 4 are detailed views of the main switching means in different positions of operation.

Referring more particularly to the drawing, a gaseous fuel burner 10 is shown in Fig. 1 as being supplied with fuel by a main fuel pipe 12. The fuel supply is under control of a combined

2

main fuel cock and switching means 14 which may form part of a thermostatic fuel control device of well-known form. The cock and switching means 14 is arranged for manual operation by a handle 15 carrying temperature indicia 13. It will be apparent that the main fuel cock and switching means 14 could be arranged for separate operation if desired and that the thermostatic device could be dispensed with.

10 Interposed in the fuel supply pipe 12 between the main fuel cock 14 and the burner 10 is an electromagnetic fuel valve 16 of any known type which may be arranged, as in this instance, to be opened when current of sufficient energizing

15 value is supplied to the solenoid 17 thereof and closed by gravity, spring or other means upon a reduction of the current value thereto below holding value. A pilot burner 18 is provided for igniting the main burner 10 and is supplied with fuel from a conduit 20 connected to the main fuel pipe 12 between the main burner 10 and the electromagnetic valve 16. It will be observed, therefore, that the electromagnetic valve 16 controls the flow of fuel to both the main burner 10

20 and the pilot burner 18. It will be apparent, however, that where the pilot burner 18 is not desired it could be dispensed with without affecting the operation of the system in its essential aspects.

25 The fuel issuing from the pilot burner 18 is adapted to be ignited by an electric resistance igniter 22. The heat of the flame of the burning fuel is adapted to cause variation in resistance of a thermal resistance element 24. The thermal

30 resistance element 24 is preferably in the form of a coil of wire of material having normally a relatively low resistance and a positive temperature coefficient of resistance and is adapted to increase appreciably in resistance when heated by the flame. While this resistance element 24 is also heated by passage of current therethrough and other types of ballast resistors or flame sensitive elements could be substituted, it will be understood to be primarily responsive to the heat

35 of the flame. The igniter 22 and thermal resistance element 24 are both located in proximity to the pilot burner 18 but, where this burner is dispensed with, these elements would be positioned in proximity to the main burner 10.

40 A second thermal resistance element 26 is included in the circuit and is also formed from a coil of wire having normally a relatively low resistance and a positive temperature coefficient of resistance. This second resistance element 26

45 is not, however, exposed to the flame of any

50

burner and is adapted to vary its resistance only due to the passage of current therethrough. As will be apparent hereinafter, the thermal resistance characteristics of the element 26 could be dispensed with and a fixed or constant resistor employed if desired.

A cut-out 28 is provided for opening the circuit of the solenoid 17 in the event of an open circuit occurring in the thermal resistance element 24. The cut-out 28 is preferably of the thermal type having time-lag operation. Such devices are constructed with predetermined time current characteristics and usually contain a heater element in addition to and affecting a fusible member which opens the circuit by passage of overcurrent.

A control relay, designated generally by the reference numeral 30, is provided for establishing desired circuit conditions during the starting and running periods of the burner. The control relay 30 is preferably of the electromagnetic type having a winding 32 and a pivotally mounted armature 34 which is rendered responsive to energization of the winding 32 by means of a core 36 to which the armature is hinged at one end. A plurality of pairs of switch contacts, in this instance two, 38 and 40, are adapted to be opened and closed by operation of the armature 34. In the arrangement shown both contact pairs 38 and 40 are closed and opened substantially simultaneously by appropriate movements of the armature 34.

Means are provided for latching the armature 34 in the closed position for a predetermined period during which the winding 32 may be de-energized. The latching means comprises a pivoted arm 42 adapted to engage and latch the armature 34 but being normally biased to free position by a spring 44. A thermal timer of any known type comprising a bimetal element 46 and heater coil 48 therefor is adapted to overcome the bias of the spring 44 to enable the arm 42 to move into latching engagement with the armature 34 when the bimetal element 46 is cold as shown in Fig. 2. The thermal timer preferably includes the so-called instantaneous reset device (not shown) generally consisting of a cold conducting surface for the bimetal element 46 which causes return of the latter to its cold position after warping therefrom.

The switching means of the main fuel cock 14 includes two movable switch arms 50 and 66 and two spaced terminals 52 and 68. The movable switch arm 50 is adapted for operative engagement with terminal 52 when the handle 15 is rotated to an intermediate position between "off" and "on" (Fig. 3). The switch arm 66 is of arcuate form and is adapted to maintain operative engagement with terminal 68 from the "on" position (Fig. 4) throughout a range of movement of the handle 15 so that various temperature settings may be selected at which the thermostat will operate. The arcuate switch arm 66 does not, however, engage the terminal 52 at any time.

The operation of the system is as follows: The main fuel cock 14 is shown in Fig. 2 in the "off" position and no fuel is being supplied to the main burner 10 or the pilot burner 18. When the main fuel cock 14 is turned toward the "on" position engagement occurs in an intermediate "on" position between the movable switch arm 50 and the terminal 52 of the switching means as shown in Fig. 3. A circuit is then established for the winding 32 of the control relay 30 which may

be traced as follows: From a source of electrical energy by line wires 54, primary of transformer 56, wire 58 connected to one terminal of the secondary of transformer 56, movable switch arm 50, terminal 52, wire 60, winding 32, wire 62 and wire 64 to the other terminal of the secondary of transformer 56.

The winding 32 being now energized from the source of current supply, the armature 34 will be operated to close the contact pairs 38, 40, provided that the contacts are not already closed, as will be hereinafter explained. As the heater coil 48 is not energized at this time the bimetal element 46 is cold and occupies the full line position shown in Fig. 2 of the drawing. In this position the bias of the spring 44 is overcome and the arm 42 is enabled to latch the armature in its contact closed position.

The normal rotation of the handle 15 of the main fuel cock 14 from "off" to "on" position will next cause disengagement of the switch arm 50 from the terminal 52 and positioning of the parts in full "on" position as shown in Fig. 4. It is apparent that the circuit for the winding 32 is opened but the contact pairs 38 and 40 remain engaged due to the latching arrangement. In this full "on" position the fuel cock 14 is fully opened and the fuel may flow in the main fuel pipe 12 at least as far as the electromagnetic valve 16 which is normally closed. The arcuate switch arm 66 is now engaged with the terminal 68 of the main switching means of fuel cock 14 and establishes a starting circuit for the safety control and ignition apparatus.

This starting circuit is in the form of an electrical bridge and may be traced from the source, line wires 54, primary and secondary of transformer 56, wire 58, switch arm 66, terminal 68, and wire 70 to junction 72 of the bridge. The first arm of the bridge may be traced from junction 72, wire 74, contact pairs 38 and 40, wire 76, igniter 22 and wire 78 to junction 80 of the bridge. The second arm of the bridge may be traced from junction 80, wire 82, solenoid coil 17 and wire 84 connected to junction 86 of the bridge. The third arm of the bridge may be traced from junction 86, wire 88, thermal resistance element 24 and wire 90 connected to junction 92 of the bridge. The fourth arm of the bridge may be traced from junction 92, wire 94, second thermal resistance element 26 and wire 96 connected to junction 72.

The cut-out 28 is connected as the detector arm in the bridge circuit by a wire 98 connecting one terminal thereof to junction 92, the opposite terminal of the cut-out 28 being connected directly to the junction 80. The circuit for the bridge is completed by a wire 100 connected at one end to the junction 86 and at the opposite end to wire 64 which is connected to the secondary of the transformer 56. If the cut-out 28 is considered of negligible impedance it is apparent that the bridge circuit is, in effect, two parallel meshes connected in series with the secondary of the transformer 56. The impedance of this circuit is relatively low and sufficient current flows to the solenoid 17 of the electromagnetic valve 16 to open this valve regardless of whether or not the thermal resistance element 24 is heated by the burning fuel. Moreover, it will be apparent that the cut-out 28 which is connected in the detector arm of the bridge circuit receives current which is maintained below its steady state operating value at all times during the starting period due

to the various arms of the bridge being in substantial balance.

As the foregoing described bridge circuit causes energization of the igniter 22, the fuel which is admitted to both the main burner 10 and the pilot burner 18 is ignited substantially simultaneously with the opening of the electromagnetic valve 16. The heat of the burning fuel will cause the thermal resistance element 24 to become effectively heated after a predetermined period which may be a few seconds.

During this starting period, the heater coil 48 of the thermal timer is also energized through a circuit which may be traced from the source, line wires 54, primary and secondary of transformer 56, wire 58, switch arm 66, terminal 68, wire 70, wire 74, contact pair 38, wire 102, heater coil 48, wire 104, wire 82 and wire 64 to the secondary of the transformer 56. The bimetal element 46 becomes heated by the heater coil 48 and warps to the broken line position shown in Fig. 2 of the drawing. Thus, the bimetal element 46 is rendered incapable of overcoming the bias of the spring 44 and the arm 42 is tripped to cause opening of the contact pairs 38 and 40. The thermal timer may conveniently operate after an eighteen-second starting period which is sufficient to allow the thermal resistance element 24 to become heated by the burning fuel. This period may be varied as desired by adjustment of the timer as will be apparent.

This operation of the contact pairs 38 and 40 terminates the starting period and marks the inception of the normal running period of the burner. The operation of contact pair 40 serves to open the first arm of the bridge circuit and deenergize the igniter 22. The bridge circuit is now converted to a circuit including the thermal resistor 24 in parallel with the solenoid 17 and cut-out 28 all in series with thermal resistor 26. The total circuit impedance is thus increased and causes a reduction in the value of the current through the solenoid 17. The current value is not reduced below that required to hold the electromagnetic valve 16 in open position if the thermal resistance element 24 has now become sufficiently heated by the burning fuel and has increased in resistance. However, if at the end of the starting period or at any time during operation of the system the flame of the pilot burner 18 should cease, then the resistance of the thermal resistance element 24 will be reduced by cooling thereof and the current to the coil 17 will be rendered insufficient to maintain the electromagnetic valve 16 in open position. Flow of fuel to both burners will then cease. This action is accelerated by making the resistance element 24 of the thermally responsive type.

It will be apparent that if the thermostatic control device previously mentioned is included as part of the main fuel cock and switching means 14 that the fuel supply to the main burner may be turned off and on thereby while the arcuate switch arm 66 which is in operative engagement with the terminal 68 maintains closed circuit conditions at the temperature setting in which the handle 15 is positioned. When the operation of the main burner 10 is no longer desired, then the handle 15 of the main fuel cock 14 may be rotated in reverse direction from "on" to "off" position. Such operation will serve to disengage the arcuate switch arm 66 from terminal 68 and cause deenergization of the coil 17 of the electromagnetic valve 16 whereupon the valve will close. Further reverse rotation of the handle 15 toward

"off" position will cause the movable switch arm 50 to become engaged with terminal 52. The winding 32 of the control relay is thereupon energized and the contact pairs 38, 40 will be closed.

As the bimetal element 46 preferably is arranged to engage a cold conducting surface as described, when in the broken line position, it will return quickly to its initial position, shown in full lines, causing the arm 42 to be moved to latching position as soon as the contact pairs 38 and 40 are opened. Thus, when the "off" position shown in Fig. 2 of the drawing is finally reached and the winding 32 is again deenergized, the contact pairs 38 and 40 may be held in closed position by the latching means due to the operation of the thermal timer described.

The winding 32 forming the electromagnetic component of the control relay is thus energized momentarily and then deenergized by the normal operation of the main fuel cock during the starting operation. Thus, the circuit timing function is performed while the power consuming element is disconnected. The usual source of noise is thus not present during normal running of the burner and the current consumption is correspondingly reduced.

It will be understood that various changes can be made in the arrangement and combination of parts and in the form of the elements herein disclosed within the scope of the appended claims without departing from the spirit of the invention.

We claim:

35. 1. An ignition and safety control system for fuel burners having a source of electrical energy, comprising electrically operable fuel controlling means movable between fuel flow permitting and preventing positions, switching means for controlling energization of said fuel controlling means from the source and operative to cause said movement thereof, means responsive to a condition caused by combustion of the fuel and electrically connected to said fuel controlling means for reducing the energy value supplied thereto sufficiently to cause movement thereof to flow preventing position in the absence of combustion, an electric resistance igniter for the fuel, control means responsive to operation of said switching means for rendering said condition responsive means ineffective to cause said movement for a predetermined period during which said condition responsive means has time to become responsive, said control means comprising a winding and switch contacts adapted to be closed for establishing a circuit from the source including said fuel controlling means, said igniter and said condition responsive means of sufficient energizing value to cause said movement to fuel flow permitting position, said winding being connected in a separate circuit with the source and adapted to be deenergized by operation of said switching means to cause opening of said switch contacts to disconnect said igniter and render said condition responsive means effective if combustion does not exist.

2. An ignition and safety control system for fuel burners having a source of electrical energy, comprising electrically operable fuel controlling means movable between fuel flow permitting and preventing positions, switching means for controlling energization of said fuel controlling means from the source and having a plurality of operative positions, means responsive to a condition caused by combustion of the fuel and electrically

ment effective if the pilot burner does not produce a flame.

4. An ignition and safety control system for fuel burners energizable from a source of current supply and comprising an electric igniter for the fuel connected in a first arm of an electrical bridge circuit, an electrically operable fuel control device in a second arm of said bridge and operable to supply fuel when current of sufficient value is supplied thereto, a pair of resistors in third and fourth arms respectively of said bridge, one of said resistors being exposed to the heat of the burning fuel for varying in resistance and causing variation in said current value, control means for rendering said igniter inoperable and said current value insufficient after a predetermined period unless said one resistor is heated, said control means comprising switch contacts operative for opening and closing said first arm and a winding for operating said contacts, switching means for connecting the source across opposite junctions of said bridge with said first and second arms and said third and fourth arms in series circuit respectively and in multiple across said junctions, said winding being connected in a separate circuit with the source and adapted to be deenergized by operation of said switching means to cause operation of said switch contacts for opening said first arm.

5. An ignition and safety control system for fuel burners having main and pilot burners and a source of electrical energy, comprising electromagnetic valve means movable between closed and open positions for controlling the fuel supply to the main burner, manually operable switching means for controlling energization of said electromagnetic valve means and having a plurality of operative positions, a thermal resistance element having a preselected temperature coefficient of resistance located in proximity of the pilot burner and electrically connected to said electromagnetic valve means for reducing the energy value supplied thereto upon variations in the resistance of said element due to the absence of a flame at the pilot burner, an electric resistance igniter for the pilot burner, a control relay effective in one position of said switching means for rendering said thermal resistance element ineffective to reduce said energy value sufficiently to cause closing of said electromagnetic valve means for a predetermined period during which said thermal resistance element has time to become heated, said control relay comprising a winding and a plurality of switch contacts adapted to be closed for establishing first and second circuits from the source in said one position of said switching means, said first circuit including said electromagnetic valve means, said thermal resistance element and said igniter and causing movement of said electromagnetic valve means to open position, said winding being connected in a third circuit with the source and adapted to be energized in another position of said switching means and immediately deenergized upon operation thereof to said one position, means responsive to closing of said switch contacts for holding the same closed when said switching means is operated to said one position thereof, and a thermal timer having a heater coil in said second circuit adapted for rendering said holding means inoperative upon expiration of said period to cause opening of said switch contacts to disconnect said igniter and render said thermal resistance ele-

6. An ignition and safety control system for fuel burners energizable from a source of current supply and comprising an electric igniter for the fuel connected in a first arm of an electrical bridge circuit having arms arranged in a sequence, an electrically operable fuel control device in a second arm of said bridge and operable to supply fuel when current of sufficient value is supplied thereto, a pair of resistors in

the third and fourth arms respectively of said bridge, one of said resistors being exposed to the heat of the burning fuel for varying in resistance and causing variation in said current value, control means for rendering said igniter inoperable and said current value insufficient after a predetermined period unless said one resistor is heated, said control means comprising a plurality of pairs of switch contacts, a winding and an armature, one said contact pair being adapted for opening and closing said first arm, switching means having a plurality of operative positions in one of which the source is connected to opposite junctions of said first and fourth arms and said second and third arms respectively, said winding being connected in a separate circuit with the source and adapted to be deenergized in said one

position of said switching means and energized in another said position thereof, latching means for said armature normally biased to free position and adapted to hold said first arm closed when said switching means is operated from said other position to said one position thereof, and a thermal timer adapted to overcome the bias of said latching means to enable the same to hold said first arm closed, said timer having a heater coil controlled by another said contact pair and connected to the source when said switching means is in said one position for rendering said timer incapable of overcoming said bias upon expiration of said period.
